UNITED STATES PATENT OFFICE.

MICHAEL GARLAND AND HARRISON W. GARLAND, OF BAY CITY, MICHIGAN, ASSIGNEES TO
THE M. GARLAND CO., OF BAY CITY, MICHIGAN, A CORPORATION OF MICHIGAN.

DISTRIBUTER AND CONVEYER.

No. 906,216.

Specification of Letters Patent.

Patented Dec. 8, 1908.

Application filed February 29, 1908. Serial No. 418,587.

To all whom it may concern:

Be it known that we, MICHAEL GARLAND and HARRISON W. GARLAND, citizens of the United States, both residing at Bay City, 5 in the county of Bay and State of Michigan, have invented certain new and useful Improvements in Distributors and Conveyers; and we do hereby declare the following to be a full, clear, and exact description of 10 the invention, such as will enable others skilled in the art to which it appertains to make and use the same.

Our invention relates to a storing device and is more particularly adapted for the 15 handling and storing of pulp wood or other timber and material.

One object is to provide means for easily and quickly conveying the wood from cars or vessels to the storage grounds and distributing it thereover.

Another object is to provide means for conveying the wood or other material from the storage grounds to the pulp mill room or other point of final discharge.

25 Other objects associated with the above are the provision of means for supplying the pulp wood or other material to any desired location in the storage ground, and the provision of means for preventing the 30 freezing of the water in the conveying flumes.

To these and other ends, our invention consists in certain novel features and combinations, such as will be more fully described 35 hereinafter and particularly pointed out in the claims.

In the accompanying drawings, Figure 1 40 is a diagrammatic plan view of one form of storing device which our invention may assume; Fig. 2 is a side elevation partly in section; Fig. 3 is an end view of a slight modification applied to the elevated distributing flume system; and Fig. 4 is a front view of the same.

45 The pulp wood or other material may be brought to the storage ground or yard by vessel, as indicated at (A) or by rail, as at (B).

The invention is located in the storage 50 yard and consists principally of a main flume elevated above the ground and a series of branch flumes extending laterally relative to the main flume, which latter is adapt-

ed to discharge its contents into any one of the branch flumes.

55 The branch flumes are each provided with discharging means at suitable points throughout their lengths whereby the material conveyed can be delivered to any point in the yard. The conveyer system extends 60 over the entire yard and the material is discharged in piles beneath the distributing conveyer.

65 Located near the ground level beneath the elevated system of distributing conveyers is a system of delivering conveyers adapted to convey the material from the yard into the pulp mill or to any other point of discharge.

In carrying out our invention we provide 70 a system of distributing conveyers elevated upon the trestles (1) (1) and comprising a main flume (2), which may extend approximately parallel with the track (B). The flume is conveniently formed with diverging 75 walls (3) (3) and a flat or other shaped bottom (4) received between the walls. The construction of the remaining flumes may be the same so that a description of one suffices for all.

80 The pulp wood or other material is discharged from the car or vessel onto a movable inclined rollway, such as (5), which leads to the foot of a traveling elevator. This elevator may be of any suitable construction, that shown comprising a frame 85 (6) provided at its lower end with wheels (7) traveling on a guide rail (8), which follows substantially parallel with the main flume (2). Near its upper end the elevator 90 frame is provided with projecting hooked arms (9) carrying rollers (10) engaging a rail (11) supported on the trestle-work (1) adjacent the main flume. An endless traveling member (12) carries folding buckets 95 (13); any suitable means being adapted to actuate the endless traveling member.

95 The elevator is adapted to be moved to any convenient point along the track (B) to accommodate itself to the position of the 100 vehicle in which the material is shipped.

The head of the elevator lies adjacent an inclined skidway (14) leading to the main flume (2). The material delivered by the rollway to the foot of the elevator is carried up and discharged onto the skidway,

which in turn discharges the material into the flume (2).

Water from a pump (15) is led to one end of the main flume by means of a pipe (16).

5 At suitable intervals, the main flume is provided with laterally-projecting chutes (17) of the same shape as the main flume. At their juncture with the main flume the chutes are widened, as at (17') to allow the 10 material to turn into the chutes from the main flume.

Sliding gates (18) extend across and close the outer ends of the chutes to prevent the discharge of material and water therefrom.

15 We also place similar gates (19) across the main flume adjacent the juncture of each chute with the flume. In practice, one gate only is necessary, since when gate (18) is in place, gate (19) is removed and vice 20 versa. Hence, gate (18) is placed in the position indicated at (19) when it is desired to discharge logs and water from the respective chutes (17).

A plurality of inclined branch flumes (20) 25 extend laterally relative to the main flume. These branch flumes are on a slightly lower horizontal plane than the main flume and their receiving ends are overhung by the discharge ends of the chutes (17), whereby to 30 receive the material discharged from the chutes.

Each branch flume is provided at intervals with removable side gates (21) (21) arranged in pairs, which gates when in position 35 form portions of the inclined side walls of the flumes.

40 A cross gate (22) is removably located across the branch flume on the down side of each pair of side gates (21), the gate (22) capable of assuming either of the positions (22) or (23).

The cross gates throughout the system 45 may be arranged at right angles to and across the flumes, but we prefer to arrange them diagonally across the flumes so that the angle of the gate will operate to shunt the material into the adjacent opening through which the material is to pass.

Pivotedly supported on the trestle-work 50 (1) directly beneath each pair of side gates (21) (21) is a pivotally supported bracket (24) adapted to swing in a horizontal plane to either side of the flume (20). Each bracket carries a slightly inclined trough 55 (25) adapted to receive the material discharged from the sides of the flumes (20) when either one of the side gates (21) is removed. The material delivered to the troughs is discharged onto the ground in 60 piles beneath the branch flumes (20).

In some instances, instead of providing a series of swinging brackets and troughs for each pair of side gates, we may employ the following construction, shown more particularly at the right of Fig. 1 and in Figs. 3 and

4. This modification consists of a pair of rails (26), one above the other mounted on the trestle-work and supporting a traveling carriage (27) to which a crane (28) is pivotally secured. The crane carries an inclined trough (29) extending in a horizontal plane lower than that occupied by the branch flumes.

The carriage is movable from end to end of the branch flume in any convenient manner, as by means of the block and tackle connections (30) and the controlling cable (31). The trough can swing in an arc of 180 degrees to discharge material in a pile at the side of the branch flumes. In order to discharge material into the traveling trough, we may equip the branch flumes with stationary chutes (32) projecting laterally from the branch flumes. The inner ends of the chutes are closed by the side gates (21). 85

The operation of the foregoing part of our invention is as follows: The material supplied from the elevator is dumped into the main flume adjacent the first branch flume and water is admitted to the main flume. Assuming the storage yard to be empty, the gate (18) is removed from its position across the end of the first chute (17) and is placed across the main flume in the position shown at (19), shunting the material into the chute which in turn discharges it into the adjacent branch flume (20). A cross gate is then placed across the branch flume in the position indicated at (22) or (23) and one or the other of the side gates (21) removed. Such side gate may be used as a cross gate. The trough adjacent the opening left in the branch flume by removing the side gate, is swung into position to receive the material delivered through said opening. The trough 95

100 discharges the material onto the ground in a pile, which pile may occupy a position determined by the arc of 180 degrees, through which the trough (25) operates. When enough material has passed through one side gate opening, the opening is closed and the opposite side gate removed to allow the discharge of material. As soon as the ground

110 beneath the first pair of side gates is filled, the side gate last removed from its position is replaced, thus opening the flume along which the material is carried until the next pair of side gates is reached, whereupon the above-described operation is repeated. As soon as the storage ground beneath one branch flume is filled, the gate is removed from position (19) in the main flume and replaced in position (18) thus opening the main flume to the next branch flume where the same procedure is repeated. But half 120

125 the work, however, is completed when the material has been dumped onto the storage ground by the system of distributing conveyors. There yet remains to be devised, some means for conveying the material to 130

the pulp machine. As one means for accomplishing this end, we have devised a system of delivering conveyers located adjacent to the ground beneath the elevated distributing 5 conveyers.

The delivery conveyer system comprises two main flumes (33) (33') connected by intermediate flumes (34) (34'), one of the main flumes (33') extending into the pulp 10 or other mill, the entire system of delivering conveyers being inclined to discharge their contents into the pulp or other mill through the flume (33'). The intermediate conveyers (34) are located alternately relative to 15 the elevated branch flumes so that the material discharged from the elevated troughs will not fall directly onto the intermediate flumes beneath.

A pipe (35) from pump (15) supplies the 20 delivering conveyer or system with water and gates (36) may be removably located at the junctures of the intermediate flumes with the main flume (33). The ends of the intermediate flumes are broadened at their 25 juncture with the main flumes to allow the material to make the turn from one flume into the other without clogging the flumes.

As it is necessary to use the delivering 30 conveyer system in winter, it is advisable to provide means for preventing the water in the delivery system from freezing, to which end we run a steam pipe (37) beneath the bottom (4) of each main and intermediate delivery flume.

It is evident that changes might be made 35 in the form and arrangement of the several parts described without departing from the spirit and scope of our invention, and hence we do not wish to limit ourselves to the exact 40 construction herein set forth.

Having thus fully disclosed our invention, what we claim as new is—

1. A distributing storage and conveyer system for yards comprising a main flume, 45 elevated branch flumes extending over the yard, means for supplying the flume with water, means for elevating material and dumping it into the flume, means for shunting the material into any one of the branch 50 flumes, means for discharging the material from the successive points in the branch flumes, a plurality of delivery conveyers located near the ground, comprising main flumes, intermediate flumes extending between 55 and connecting the main flumes, and means for supplying the delivery conveyer system with water.

2. A distributing storage and conveyer system comprising a series of elevated distributing 60 conveyers, means for supplying material and water thereto, means for discharging the material from different points in the elevated conveyers, a plurality of delivery conveyers located near the ground, and 65 means for supplying water thereto.

3. A distributing storage and conveyer system comprising a series of elevated distributing conveyers, means for supplying material and water thereto, means for discharging the material from different points 70 in the elevated conveyers, a plurality of delivery conveyers located near the ground, means for supplying water thereto, and means for preventing the water from freezing.

4. A distributing storage and conveyer system comprising a main flume, adapted to receive a liquid carrying-medium, a traveling elevator for supplying material to any point in the flume, stationary branch flumes 80 projecting laterally away from the main flume, means for discharging the liquid and the material carried thereby into any one of the branch flumes, and means for discharging the material and liquid from any one of the 85 branch flumes at points intermediate its ends.

5. A distributing storage and conveyer system comprising a main flume, means for discharging material into the flume, chutes communicating with and projecting laterally from the main flume at intervals, the chutes being broadened at their junctures with the main flume, cross-gates for closing the ends of the chutes and for shunting material from the main flumes into the chutes, 95 branch flumes into which the chutes deliver the material, and means for discharging the material from the branch flumes at intermediate points in their lengths.

6. A distributing storage and conveyer 100 system comprising a main flume, means for discharging material thereinto, chutes communicating with and projecting laterally from the main flume at intervals, means for directing the material into any of the chutes, 105 and for closing any one of the chutes, a series of branch flumes located on a plane beneath the chutes and adapted to receive material from the chutes, sections of the opposite sides of each branch flume being removable to leave discharge openings, and gates for preventing the passage of material past such openings.

7. A distributing storage and conveyer system comprising a main flume, means for discharging material thereinto, a plurality of branch flumes, means for discharging material from the main flume into any one of the branch flumes, sections of the opposite sides of each branch flume being removable 115 to leave discharge openings, and gates for preventing the passage of material past such openings.

8. A distributing storage and conveyer system comprising a main flume, adapted to receive a liquid conveying-medium, means for supplying the flume with material to be conveyed, a branch flume extending laterally away from the main flume, means for delivering material and liquid from the main 125 130

flume into the branch flume, and means for discharging the material and liquid at points intermediate the length of the branch flume.

9. A distributing storage and conveyer system comprising a main flume, means for supplying the flume with material, a plurality of branch flumes, means for delivering material from the main flume into any one of the branch flumes, means for discharging the material from points intermediate the length of the branch flumes, and swinging troughs into which the material from the branch flumes is discharged and by which it is dumped onto the storage ground.

15 10. A distributing storage and conveyer system comprising a main flume, means for supplying the flume with material, a plurality of branch flumes, means for delivering material from the main flume into any one 20 of the branch flumes, means for discharging the material from points intermediate the length of the branch flumes, and pivotally-supported troughs adapted to travel along side the branch flumes to receive the material discharged therefrom and to deliver it to any suitable point.

11. A distributing storage and conveyer system comprising a main flume, means for supplying the flume with material, a plurality of branch flumes, means for delivering material from the main flume into any one 30 of the branch flumes, means for discharging the material from points intermediate the length of the branch flumes, and a series of 35 conveying flumes arranged beneath the branch flumes and adapted to receive material discharged from the branch flumes and lead it to a predetermined point.

12. A distributing storage and conveyer system comprising an elevated main flume, a series of elevated branch flumes, means for diverting material from the main flume into any one of the branch flumes, means for discharging the material from the branch flumes at intermediate points in their lengths, a series of inclined delivery conveyers located on a plane beneath the branch flumes, the delivery conveyers comprising main flumes and intermediate flumes connecting the main flumes.

50 13. A distributing storage and conveyer system comprising a plurality of delivery conveyers, the delivery conveyers comprising main flumes and intermediate flumes connecting the main flumes, the intermediate flumes being inclined to discharge into one of the main flumes, and means for shunting material into one or the other of the intermediate flumes.

14. A distributing storage and conveyer system comprising a plurality of delivery conveyers, the delivery conveyers comprising main flumes and intermediate flumes connecting the main flumes, the intermediate flumes being inclined to discharge into one 60 of the main flumes, means for supplying the delivery flumes with water and means for preventing the water from freezing.

In testimony whereof, we affix our signatures in presence of two witnesses.
